[57] ABSTRACT

A rotary fluid machine of the kind that is to be actuated by any fluid under pressure in which a rotor (15) carrying a piston member (154) rotates continuously when the machine is in operation about the axis (AA1) of an annular chamber (21), the piston member (154) is geared to rotary obturators (17_A, 17_B) that rotate in sealing chambers 21₁ in an annular member 21₂ projecting into the annular chamber 21 about an axis (BB1, CC1) substantially parallel to said axis (AA1) of the annular chamber (21) and the rotary obturator has a recess into which a part of the piston enters during rotation to provide a working section in the cylinder as working fluid is fed to the piston. The machine is characterized in that the piston member (154) has a frusto-conical peripheral surface (G1, G2) that seals with a frusto-conical mating surface of its annular chamber, the two surfaces being kept into sealing contact by an axial force of the axis (AA1) of a right cone common to both said surfaces.

FIG. 3

FIG. 3A

ROTARY PISTON MACHINE WITH MATING FRUSTOCONICAL SEALING SURFACE

This is a continuation, of application Ser. No. 160,779, filed June 18, 1980, now abandoned.

DESCRIPTION

This invention relates to a rotary fluid machine of the kind (hereinafter referred to as the kind set forth) comprising a rotor carrying a piston member that rotates continuously when the machine is in operation about the axis of an annular chamber, the piston member is mechanically linked to a rotary obturator that rotates in a sealing chamber about an axis substantially parallel to said axis of the said annular chamber and the rotary obturator has a recess into which a part of the piston enters during rotation to provide a working section in the cylinder as working fluid is fed to the piston.

The term fluid machine is to have a wide meaning to embrace inter alia an engine, a pump, a compressor or a brake in which work is done.

Such rotary fluid machines are known for example from the specifications of United Kingdom Patent Specification Nos. 365,520 to Elrick and No. 407,661 to 25 Societe Les Turbo-Moteurs Guy and from U.S. Pat. No. 3,354,871 to Skrob. It has proved exceptionally difficult to seal the rotary obturator and without effective sealing the engine is inefficient and this difficulty is fully explained by Skrob (3 17-21).

According to the present invention there is provided a rotary fluid machine of the kind set forth wherein the piston member has a frusto-conical peripheral surface that seals with a frusto-conical mating surface of the annular chamber, the two frusto-conical surfaces are kept in sealing contact by an axial force that is directed along the axis of a right cone common to both said frusto-conical surfaces, the axis being the axis of rotation of the piston member.

In one arrangement the rotary obturator is also of 40 frusto-conical form and axially forced into sealing contact with its sealing chamber that is of complementary shape. Alternatively the rotary obturator may be one of the divided forms described in my co-pending application Ser. No. 482,378, which is a continuation of 45 application Ser. No. 160,761, filed June 18, 1980, now abandoned.

The invention will be more fully understood from the following description given by way of example only with reference to the figures of the accompanying drawings in which:

FIG. 1 is an elevation in section of a rotary machine of the invention, and FIG. 1A is a part section of the piston and cylinder in mating contact.

FIG. 2 is a part section similar to FIG. 1 of an alternative arrangement to a larger scale.

FIG. 3 is a view in perspective of a part of a piston and one rotary obturator of an alternative construction and FIG. 3A is a detail in section.

Referring now to FIG. 1 a block 10 has a head 11 spigot jointing at 12 and carrying a centrally journalled power shaft 13 in bearings 14₁, 14₂ and 14₃. The shaft 13 carries a rotary piston member 15 keyed at 15₁ and splined at 15₂ to said shaft with allowance for movement of the key at 15₃. The piston has three working 60 piston parts of which one only is shown at 15₄ said piston entering a piston recess such as 16 in rotary obturators 17A and 17B of a diametrically opposed pair, its

fellow obturator being at 17B. Each rotary obturator is keyed at 18₁, 18₂ and splined if necessary to a shaft 19₁, 19₂, each key is provided with an allowance for movement of the shaft at 18₃, 18₄. Gears 20₁, 20₂ on shafts 19₁, 19₂ mesh with gear 20₃ on shaft 13 that has a power output end at 13₁.

Steam or other suitable working fluid is fed to annular chamber and expansion cylinder 21 containing the rotary piston 15 by means of a metering unit shown generally at 22. Any suitable metering unit may be used and one such unit is described in my co-pending Application No. 482,378. Steam is directed through channels 33A and 33B through openings 34A and 34B in the obturators to the recess 16 where the steam applies a force on the piston 15.

Rotary piston 15 has a frusto-conical peripheral sealing surface 15A that seals with a like frusto-conical sealing surface at 15B of the wall 21₂ of the annular chamber 21 shown inset in FIG. 1A and taken at a section station away from the rotary obturators. Mating surfaces 15A, 15B are each part of a common right cone having its axis on the axis AA₁ of shaft 13 as represented by the single incomplete generator G₁, G₂. Suitable clearance for take-up of wear is left at position CL₁.

The rotary piston 15 is spring urged along the axis AA₁ by helical compression spring 23. Similarly frusto-conical rotary obturators 17A, 17B are individually spring urged by helical compression springs 24A, 24B along the axis BB₁, CC₁ of their respective shafts 19₁, 19₂ so that said obturators 17A, 17B seal against complementary mating frusto-conical surfaces of their respective sealing chambers 21₁ in the annular member 21₂ and thus with wear the all important seal is efficaciously maintained, a suitable clearance being left at position CL₂, CL₃.

In FIG. 2 a rotary obturator shown generally at 17C is of a form described and claimed in my co-pending application Ser. No. 482,378. The rotary obturator has two parts 17C₁, 17C₂ that are spring urged by a spring 35, as exemplified in FIG. 3A, helically along line 25 to expand continuously and thus effect good sealing at all times, irrespective of wear and thermal expansion with the internal surfaces of its sealing chamber. The piston rotor 15 as in FIG. 1 mates on frusto-conical surface of a common right cone shown by the single generator G₃, G₄ that meets when extended on the center line AA₁ of piston shaft 15.

In FIG. 3 a piston 26 of a different construction from that of FIGS. 1 and 2 is of a singularly robust form. The piston 26 has an internal piston face 26_A co-operating with a piston recess 27A in a separable rotary obturator shown generally at 17D that is able continuously to expand on a helical surface 28 so that surfaces 29₁, 29₂ always mate with the surfaces 26₁, 26₂ of the piston 26. It is to be noted that the piston surface 26₃ is also frusto-conical to mate with a similar surface 31 of the obturator (FIG. 3A). The piston also has a frusto-conical sealing surface at 32 that mates with a similar wall surface (not shown). The piston member is provided with a piston working part 26A annularly enclosed on three sides 26₁, 26₂, 26₃; the obturator sealing with two of the said opposed sides viz: 26₁, 26₂.

I claim:

1. A rotary piston machine comprising a housing having an annular chamber, shaft means carrying a rotary piston member for continuous rotation about an axis of said annular chamber when the machine is in operation, means mechanically linking said piston mem-

ber to a rotary obturator means rotatably received in a sealing chamber for rotation about an axis substantially parallel to said axis of rotation of said piston member, said rotary obturator means having a recess into which a part of the piston member enters during rotation to provide a working section in said annular chamber as a working fluid is fed to said piston member, said piston member having a frusto-conical peripheral surface that seals against a frusto-conical mating surface of the annular chamber, and biasing means maintaining said two frustoconical surfaces in sealing contact, said biasing means exerting a force that is directed along an axis of a right cone common to both said frusto-conical surfaces, said cone axis being the axis of rotation of said rotary piston member.

2. A rotary piston machine according to claim 1 wherein the rotary obturator means comprises at least two parts having mating engagement along an incline, and biasing means continuously urging one of said parts relative to the other along said incline to keep at least a part of an exterior surface of said obturator means in

sealing contact with the juxtaposed interior surface of its sealing chamber.

3. A rotary piston machine according to claim 2 wherein the incline is a helical surface.

5. A rotary piston machine according to claim 1, in which said rotary obturator means and said sealing chamber have mating surfaces of complementary frusto-conical form, and a biasing means axially urges said rotary obturator means into sealing contact with said sealing chamber.

10. 6. A rotary piston machine according to claim 4 in which the biasing means urging said mating surfaces of said frusto-conical obturator means and sealing chamber into sealing contact is a spring means.

15. 7. A rotary piston machine according to claim 5 wherein one of the frusto-conical surfaces of any mating pair of such surfaces is on a member attached to a splined shaft allowing axial movement along said shaft.

20. 8. A rotary piston machine according to claim 1 wherein the piston member has piston working parts annularly enclosed on three sides, said obturator means sealing with two opposed sides of the said annularly enclosed sides of the piston member.
